[57] CLAIM

The ornamental design for a plate rack, as shown and described.

DESCRIPTION

FIG. 1 is a perspective view of a plate rack showing my new design;

FIG. 2 is a left side elevational view thereof, the right side being a mirror image thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a perspective side view of a second embodiment of the plate rack shown in FIG. 1; the opposite side being a mirror image thereof.
